DESIGN FOR A BROOCH PIN

Clarice L. Leonhardt, Miami, Fla.

Application October 24, 1944, Serial No. 115,940

Term of patent 7 years

(Cl. D45—19)

To all whom it may concern:

Be it known that I, Clarice L. Leonhardt, a citizen of the United States of America, residing in Miami, county of Dade and State of Florida, have invented a new, original, and ornamental Design for a Brooch Pin, of which the following is a specification, reference being had to the accompanying drawing, forming part thereof.

Fig. 1 is a plan view of a brooch pin showing my new design.

Fig. 2 is a rear view thereof.

Fig. 3 is an edge view.

I claim:

The ornamental design for a brooch pin, substantially as shown.

CLARICE L. LEONHARDT.
